UNITED STATES PATENT OFFICE.

MARSHALL N. JARVIS, OF PORTLAND, CONNECTICUT.

CURTAIN-FASTENER.

1,194,502.

Specification of Letters Patent. Patented Aug. 15, 1916.

Application filed May 26, 1916. Serial No. 100,027.

To all whom it may concern:

Be it known that I, MARSHALL N. JARVIS, a citizen of the United States, residing at Portland, in the county of Middlesex and 5 State of Connecticut, have invented a new and useful Improvement in Curtain-Fasteners; and I do hereby declare the following, when taken in connection with the accompanying drawings and the characters of 10 reference marked thereon, to be a full, clear, and exact description of the same, and which said drawings constitute part of this application and represent, in—

Figure 1 a broken view in front elevation, showing one of my improved fasteners as in use. Fig. 2 a side view of the same. Fig. 3 a sectional view of the device on the line 3—3 of Fig. 2. Fig. 4 a sectional view of the device on the line 4—4 of Fig. 1. 20 Fig. 5 a view of the gromet of the device which is mounted upon the curtain and shown as removed from the post. Fig. 6 a detached view in elevation of the post and its mounting-plate. Fig. 7 a side view of 25 the same. Fig. 8 a view in elevation of the rotary locking-member detached, with its ball and ball-retaining spring in place. Fig. 9 a side view of the post shown at a right angle to its position in Fig. 7. Fig. 10 a 30 perspective view of the outer washer. Fig. 11 a corresponding view of the inner washer.

My invention relates to an improvement in curtain fasteners particularly designed for use in automobile construction but available wherever like curtains are used, the 35 object being to produce a convenient, durable and reliable fastening which will not under any conditions of jar or strain become unfastened.

With these ends in view, my invention 40 consists in a curtain fastener having certain details of construction as will be hereinafter described and pointed out in the claims.

In carrying out my invention, as herein 45 shown, I employ a solid post 5 formed at its outer end with an integral oblong locking-head 6 the outer face of which is rounded and which is separated from the body of the post by a concentric neck 7 beyond which 50 the ends 8 of the head overhang. The inner end of the post is recessed as at 9 for the formation of an annular flange 10 adapting

it to be fastened by spinning or swaging into a circular hole 11 formed in an oblong plate 12 formed near its ends with counter-sunk screw holes 13 for the reception of screws 14 by means of which the plate 12, and hence the post 5, is rigidly secured in place. The said post is formed with two longitudinally arranged clearance-grooves 15 and with two locking-recesses 16 located opposite each other and quartering with respect to the grooves 15. The said grooves 15 and locking-recesses 16 alternately receive a ball 17 located in a circular hole 18 formed in the body portion of a cup-like rotatable locking-member 19 the outer end of which is diametrically cut to form an oblong locking-opening 20 large enough for the free passage of the head 6 of the post 20 with its overhanging ends 8. Preferably the material cut away for the formation of the opening 20, is turned outward to form two oppositely located finger-pieces 21 by which the locking-member 19 is rotated in 25 locking and unlocking the fastener. The outer ends of the fingers 21 are turned downward to engage with the outer face of a cup-like housing 22 having a central opening 23 through which the locking-member 19 30 passes. The said housing 22 is enough larger in diameter than the locking-member 19 for the production of an annular space 24 which receives the locking-ball 17 and a circular spring 25 between the separated 35 ends of which the said ball is located, the said spring exerting a constant effort to crowd the ball into the circular hole 18 in the locking-member 19 so that the inner portion of the ball may co-act with the 40 grooves 15 and recesses 16 of the post 5. As the ball rides out of the said grooves and recesses, it moves radially with respect to the longitudinal axis of the post by forcing the ends of the circular spring 25 apart. 45 The inner end of the housing 22 is entered into an annular groove 26 in an inner washer 27 placed against the inner face of the curtain 28 which is pinched between it and an outer washer 29 placed upon the 50 outer face of the curtain and formed at opposite points upon its edge with fingers 30 which pass through oppositely located notches 31 in the edge of the inner washer

27, the said fingers 30 being bent inward at a right angle to the washer 29 and then forced through the curtain 28 and through the notches 31 and then bent inward as at 5 32 for firmly holding the two washers upon the opposite sides of the curtain with the same pinched between them. The said outer washer 29 is formed with a central opening 33 large enough to permit it to be set over 10 the housing 22 which is passed outward through an opening 34 in the curtain 28 when the device is being assembled.

In so far as the inner and outer washers 27 and 29 are applied directly to the curtain, they correspond to and take the place 15 of the gromet of an ordinary curtain-fastener, and for convenience I shall hereafter refer to them as together forming the gromet of my improved device. My device is therefore characterized by having its gromet provided with a rotatable locking-member 20 adapted to be engaged with, and disengaged from, a rigid post fastened to some portion of the car.

25 The operation of my improved fastener is as follows: The locking-member 19 is turned one way or the other as required to register its oblong opening 20 with the fixed head 6 of the post 5 which is mounted upon the car-body, represented by 35. The gromet is then slipped over the post 5, at which time the ball 17 enters one or the other of the clearance-grooves 15 thereof, these grooves being arranged so that they will be in line 35 with the said ball 17 at the same time that the slot 20 is registered with the oblong head 6 of the post 5. When the gromet is in position over the post 5, as described, the opening 20 in the locking-member 19 will coincide with the neck 7 of the post, thus permitting the locking-member 19 to be rotated in either direction for a quarter turn, whereby the ball 17 will be forced, against the tension of the spring 25, to ride out of the 40 groove 15 in which it happens to be located, and over the face of the post, until it enters one or the other of the two recesses 16 into which it is forced by the spring 25 with the effect of holding the locking-member 45 against rotation. The quarter turn rotation of the member 19 having now placed the opening 20 at a right angle to the oblong head 6, as shown in Fig. 1, the device is securely fastened, since the gromet organization cannot now be removed from the post 55 except by the manual rotation of the locking-member 19 for a quarter turn in one direction or the other for re-registering the locking-ball 17 with one or the other of the 60 two grooves 15, whereby the opening 20 is again registered with the oblong head 6 so as to permit the gromet to be slipped off from the same.

Under my improved construction, the post 65 is made in one piece and not liable to suffer

from blows as are the posts of the ordinary curtain-fasteners which mount a turn-button head. Under my construction, the manually operated part, namely, the rotary locking-member, by being connected with the 70 gromet, and hence attached to the curtain, is less liable to injury. Furthermore, the rotary locking-member is so firmly held in its locked position that it will not, in any jarring of the car, work loose. If desired, 75 the longitudinal clearance-grooves of the post might be omitted, though the device is more conveniently operated with them, but no more securely locked.

I claim:

1. In a curtain fastener, the combination with a post having an oblong overhanging locking-head, of a gromet adapted to be applied to a curtain, and a rotary locking-member having swivel connection with the 80 said gromet and adapted on partial rotation to co-act with the overhanging locking-head of the post to connect the same and the gromet.

2. In a curtain fastener, the combination 85 with a post having an oblong overhanging locking-head and formed with locking-recesses, of a gromet adapted to be applied to a curtain, a rotary locking-member having swivel connection with the said gromet, and a locking-ball carried by the said member and brought into position by the partial rotation thereof for co-acting with a locking-recess of the post.

3. In a curtain fastener, the combination 90 with a post having an oblong overhanging locking-head, and formed with longitudinal clearance-grooves and with locking-recesses, of a gromet adapted to be applied to a curtain, a rotary locking-member having swivel 95 connection with the said gromet, and a locking-ball carried by the said member and co-acting with the said grooves and locking-recesses of the post.

4. In a curtain fastener, the combination 100 with a post having an overhanging head, of a gromet, a rotary locking-member carried thereby, a locking-ball carried by the said member and coacting with the said post, a housing inclosing the said rotary locking-member, and a spring located within the said housing and coacting with the said ball.

5. In a curtain fastener, the combination 105 with a post having an overhanging head and formed with a clearance groove and a locking recess, of a gromet provided with a rotary locking-member, a locking-ball located in an opening formed in the said locking-member and coacting with the said groove and the said recess in the said post, a housing inclosing the said locking-member, and a circular spring located in the space between the said member and housing and co-acting with the said ball for yieldingly 110 holding the same in place.

6. In a curtain fastener, the combination with a post having an overhanging head, of a gromet, a rotary locking-member carried by the said gromet, formed with a locking-opening and provided with finger-pieces, a housing interposed between the said finger-pieces and the gromet, a locking-ball located in an opening in the said housing and co-acting with the said post, and a spring located between the housing and the locking-¹⁰ member for coaction with the said ball which it holds in engagement with the said post.

MARSHALL N. JARVIS.
